MOTOR MOUNTING

Application filed December 7, 1928. Serial No. 324,435.

This invention relates to improvements in motor mountings, more particularly adapted for rigidly attaching electric motors to sewing machine heads to hold the motor pulley 5 in frictional engagement with the sewing machine hand wheels.

This application is a continuation in part of our co-pending application, Serial No. 106,978, filed May 5, 1926.

10 One of the objects of the invention is to provide an exceedingly simple and inexpensive mounting by which the motor will be held in fixed position, with its pulley in permanent driving relation to the sewing machine hand wheel, but which will permit removal of the motor when desired.

Another object is to provide a motor mounting which will occupy practically no space exteriorly of the sewing machine head, 20 by means of which the motor will be positioned closely to the head, and both will require a minimum of space.

In the drawings:

Figure 1 is a fragmentary end view of a 25 sewing machine head with motor attached by means of our improved mounting.

Figure 2 is a side elevation of the same.

Figure 3 is a fragmentary view similar to Figure 1, showing a modification of the invention.

In the drawings, the sewing machine head is indicated at 5, and the revoluble hand wheel or fly wheel at 6. In that embodiment of the invention shown in Figures 1 and 2, 35 the motor 7 has flattened sides. The motor pulley 8 is mounted on the rotatable shaft 9 to rotate therewith, and is in frictional engagement with the fly wheel 6 when the motor is mounted on the head 5.

40 A flat plate member 10 is secured to the rear flattened face of the motor 7. If desired, the motor casing may have a thickened rear wall instead of being provided with the attached plate 10. The plate 10 is provided 45 with a plurality of spaced apart, circular recesses 11, the walls of which are screw-threaded for a purpose to be described.

The side walls of the head 5 are provided 50 with a plurality of oppositely positioned apertures 12, the uppermost one in each side

wall being positioned just below the enlarged portion 13 of the head 5. Extending through these apertures from the forward side wall of the head 5 to the other, and slightly beyond the rearward surface of the latter, are a plurality of headed bolts 14, having screw-threaded ends 15, adapted to enter and engage the screw-threaded recesses 11 of the motor plate 10. The apertures 12 and the bolts 14 are so arranged that the bolts will not interfere with the usual sewing machine mechanism in the head. For this purpose, they are preferably positioned as shown in Figure 2 of the drawing.

Between the side wall of the head 5 and the plate 10 of the motor are pads 16, preferably of felt or other compressible material, which prevent close contact of the metallic parts and also provide means for slight adjustment between motor and sewing machine head for maintaining the pulley 8 in proper frictional engagement with the fly wheel 6.

Referring now to the modified form of the invention shown in Figure 3, it will be seen that the motor 17 is round in transverse, vertical section instead of having flattened sides. There is attached to the rear side of said motor 17 a specially shaped plate 18. This plate may be attached to the motor in any desired manner. One side of the plate 18 is complementary to the curved side of the motor 17 and the other side of the plate 18 is substantially flat. This plate is also provided with three recesses 19, screw-threaded to receive the screw-threaded ends of the bolts which have also been indicated at 14 and are similar to the bolts 14 shown in Figures 1 and 2. The locations of the apertures in the side walls of the head 5 differ slightly in the form shown in Figure 3 from that shown in Figures 1 and 2, because the plate 18 is not as wide from top to bottom as is the plate 10. In Figure 3, the pads 16 are not shown, but they may also be used between the head 5 and plate 18 for the purpose heretofore set forth.

The motor may be easily attached by our mounting and as readily removed for repairs or cleaning, if desired. While attached, it is in proper driving relation to the fly wheel.

Obviously, changes in details of construction may be made without departing from the scope of our invention, and we do not intend to be limited to the precise form shown and described, except as pointed out in the appended claims.

We claim as our invention:

1. In a sewing machine, the combination of a sewing machine head, a fly wheel, a motor, having a shaft and a pulley on the shaft, and means for mounting the motor on the head with the pulley in frictional engagement with the fly wheel, said means including a plate member on one side of the motor having a plurality of screw-threaded recesses, and a plurality of headed bolts, having screw-threaded ends, extending through the sewing machine head, the screw-threaded ends extending beyond the head in engagement with said screw-threaded recesses of the plate member. 80
2. In a sewing machine, the combination of a sewing machine head, a fly wheel, a motor, having a shaft and a pulley on the shaft, and means for mounting the motor on the head with the pulley in frictional engagement with the fly wheel, said means including a plate member on one side of the motor having a plurality of screw-threaded recesses, 85 and a plurality of headed bolts, having screw-threaded ends, extending through the sewing machine head, the screw-threaded ends extending beyond the head in engagement with said screw-threaded recesses of the plate member, and pads of compressible material between the motor and the sewing machine head. 90
3. In a sewing machine, the combination of a sewing machine head having a plurality of oppositely positioned apertures in its front and rear side walls, a fly wheel, a motor having a shaft and a pulley on the shaft, and means for mounting the motor on the head with the pulley in frictional engagement with the fly wheel, said means including a plate member on one side of the motor having a plurality of screw-threaded recesses located to register with the apertures in the head, and a plurality of headed bolts, having screw-threaded ends, extending through the apertures of said sewing machine head, the screw-threaded ends extending beyond the head in engagement with said screw-threaded recesses of the plate member. 95
4. In a sewing machine, the combination of a sewing machine head, a fly wheel, a motor having a shaft and a pulley on the shaft, and means for mounting the motor on the head with the pulley in frictional engagement with the fly wheel, said means including a plate member on one side of the motor having a plurality of screw-threaded recesses, and a plurality of headed bolts, having screw-threaded ends, extending through the sewing machine head, the screw-threaded ends ex- 100

tending beyond the head in engagement with said screw-threaded recesses of the plate member, the location of the bolts being arranged so that the bolts pass through parts of the head not occupied by sewing mechanism. 70

In testimony, that we claim the foregoing as our invention, we affix our signatures, this 3rd day of December, 1928.

EDWIN Q. BANGS. 75
WILLIAM ERNST.
